Term of patent 14 years

(Cl. D35—2)

FIG. 1.

FIG. 2.

FIG. 3.

FIG. 5

FIG. 4.

FIGURE 1 is a side elevation of a garden implement handle showing my new design;

FIG. 2 is a top plan view thereof;

FIG. 3 is an end elevation taken in the direction of line 3—3 of FIGURE 1;

FIG. 4 is a bottom plane thereof; and

FIG. 5 is a side elevation of the implement handle disclosed in FIGURE 1, mounted on the blade member in an alternate position.

The fragmentary broken line representation of the implement blade is shown for illustrative purposes only.

I claim:

The ornamental design for a garden implement handle, substantially as shown and described.
